UNITED STATES PATENT OFFICE.

MARCUS A. HARDY, OF NEWPORT, RHODE ISLAND, ASSIGNOR TO GEORGE H. REYNOLDS, OF NEW YORK, N. Y., AND MARTIN HUBBE, OF BAYONNE, NEW JERSEY, ONE-FOURTH TO EACH.

SUBMARINE TORPEDO-BOAT.

SPECIFICATION forming part of Letters Patent No. 243,888, dated July 5, 1881.

Application filed April 26, 1879.

To all whom it may concern:

Be it known that I, MARCUS A. HARDY, of Newport, in the county of Newport and State of Rhode Island, have invented certain new and useful Improvements in Marine Torpedoes, of which the following is a specification.

Certain of my improvements consist in the combination, with a marine torpedo and an electric circuit, of a pin or bar adapted to complete said circuit and effect the firing of the torpedo; also, in the combination, with a marine torpedo and an electric circuit, of two resistance-coils controlling the firing of a cartridge, one being adapted to be cut out by the contact of a firing-pin at the bow of the torpedo with any object, and the other being adapted to be cut out by the operator at will.

Other improvements consist in the combination, with the exhaust-pipe of the propelling-engine, of a hollow propeller-shaft, whereby the motive agent may be exhausted into the water in rear of the torpedo.

Other improvements consist in a novel cable reel or drum composed of parts capable of being readily detached and attached.

Other improvements consist in details to be hereinafter set forth.

In the accompanying drawings, Figure 1 represents a longitudinal section of the bow portion of a marine torpedo embodying certain of my improvements. Fig. 2 represents an enlarged longitudinal section of the extreme bow. Fig. 3 is an enlarged partly-sectional side view of the firing-pin. Fig. 4 represents the operator's key-board for manipulating and firing the same. Fig. 5 is a partly-sectional side elevation of the stern portion of a marine torpedo, illustrating provision for conducting the motive agent as it is exhausted through the propeller-shaft, as also the drum in which the cable is arranged. Fig. 6 is a longitudinal section of a reel for paying out the cable, embodying some of my improvements. Fig. 7 is a similar view of the same made into a drum. Fig. 8 is a transverse section of the same. Fig. 9 is a longitudinal section of a modified form of reel. Fig. 10 is a similar view of the latter made into a drum. Fig. 11 is a cross-section thereof; Fig. 12, a longitudinal section of a reel of another modified form.

Fig. 13 is a similar view of the latter made into a drum, and Fig. 14 is a cross-section thereof.

Similar letters of reference designate corresponding parts throughout the figures.

Considering first Figs. 1, 2, 3, and 4, B designates the bow part of the shell or hull of a marine torpedo, which is made of metal, and is furnished at its extreme point with a bar, A A A', which is free to slide in a casting or other slideway, C, and is shown as kept watertight by stuffing-box a. This bar A A A' is represented as made in three pieces or sections, consisting of two end pieces or sections, A, of metal, and a central piece or section, A', of hard rubber or its equivalent, to which the end pieces are secured in any suitable manner—for instance, by being screwed into the same.

To the inboard end of the casting or slideway C is secured a short tube, D, into which is screwed or otherwise fastened a plug, E, of hard rubber or equivalent material, provided with two small binding-screws, F and G, passing through the plug E and securing two projections consisting of springs H I, which may be of brass, to the inside of the plug E.

J designates a resistance-coil the ends of whose wires are attached to the binding-screws F and G.

K is a wooden or other suitable partition dividing the extreme point or bow from the magazine L, containing the explosive charge, and M is a cartridge one of the wires of which connects with the outside plating of the shell or hull B, and there communicates with the ground, while the other wire leads through the partition K and is secured to the binding-screw F.

The line-cable N leads from the binding-screw G, Fig. 1, to the binding-screw O (see Figs. 2 and 4) of the operator's key-board, which is in connection with one side of a circuit-closer or switch, P, the other side of which leads to a pole-changer or ordinary key, Q, having the usual connection with a battery, R, and ground-plate S. By means of the pole-changer or key Q an electric current can be established.

T is a resistance-coil the ends of whose wires lead to the two sides of the switch P.

When the sliding bar A A A' and the handle

b of switch *P* on the key-board are in the position shown in drawings, both resistance-coils *J* and *T* are in circuit, but offer such a resistance that when the firing-key *Q* is turned to 5 "Fire", it is impossible to fire the cartridge *M* by means of battery *R*. If, however, one or the other of the coils is cut out or short-circuited, the resistance is reduced to such an extent as to enable the battery *R* to fire the 10 cartridge *M* with ease. Thus, if it is desired to fire at a given time or signal, the handle *b* of switch *P* is turned to "At will," thereby allowing the current to pass through the switch *P*, instead of going through the resistance-coil 15 *T*; or, in the other case, if desired to fire by contact, the projecting bar *A A A'*, as soon as it strikes the object to be attacked, slides in-board between the two springs *H* and *I*, whereby the inner end of the bar *A A A'* becomes 20 insulated from the slideway *C* by the rubber or equivalent middle piece or section, *A'*, of bar *A A A'*, passing partly out of its slideway *C* on the inside, and thus causing the current to pass through the two springs and binding-screws instead of through coil *J*.

In place of using a rod and springs to close the circuit in the bow, any other known device may be substituted, as two copper plates or disks with a water-space between, &c.

30 Turning now to Fig. 5, *B* designates the shell or hull of a marine torpedo. It has an upwardly-tapering stern, and is furnished with a screw-propeller, *B'*, mounted on a shaft, *B²*, as also with a rudder, *B³*. The propeller-shaft *B²* is represented as driven through gear-wheels *B⁹*, and hollow throughout its extent, so as to form a conduit through which the motive agent employed for propulsion may be exhausted.

In this example of my invention the exhaust-pipe *B⁴* of the engine is shown as extending entirely through the propeller-shaft and slightly beyond the end thereof, and as furnished at the end with an inwardly-closing valve, *v*, whereby it is controlled, a spring, *s*, arranged around its stem, between a bridge-piece, *t*, in the said pipe, and a collar, *u*, on said stem being employed to close the valve when the engine is not exhausting. The engine is preferably arranged in a compartment, *B⁵*, filled with 45 water, and when it is so filled with water no stuffing-box is necessary where the exhaust-pipe *B⁴* enters the propeller-shaft. If, however, no water is to be admitted, a stuffing-box will be necessary to preclude leakage at this 55 point.

UZ designates a cable-drum, hereinafter fully described, arranged in a compartment, *B⁶*, lengthwise of the boat, and containing the cable of electric conductors, whereby the operation of the component parts of the torpedo are controlled. It is shown as communicating with a pipe, *B⁷*, whereby the said cable is conducted aft of the screw-propeller and rudder, and is precluded from fouling with these devices.

65 Turning now to Figs. 6, 7, and 8, *U* designates two circular heads, of brass, iron, or other

suitable material; provided at their periphery with flanges *c* to enhance their stiffness, and near the center with circular flanges *d*, into which are fitted cast-iron or other journals, *V*. They have also central openings, *k*. The center barrel or body of the reel consists of three cylindrical segments, *W*, of sheet metal, strengthened by and riveted to bars *e*, the ends of which pass through the two journals *V*, and are screwed up tight till the sheet-iron segments are brought or forced up solidly against the heads *U*, thus making the reel like a solid one. The two journals rest in a frame in which the reel rotates. After winding on 70 the cable until it fills the reel (which may be done in the usual manner) the same is inclosed between the heads *U* by a light metal case, *Z*, (see Fig. 6 and the large dotted circle in Fig. 7,) composed of two parts connected at the 75 bottom by hinges *f*, so as to be capable of opening out in two halves, and fitted at the upper edges with two angle-bars, *g*, by means whereof, in conjunction with bolts *h*, the case may be clamped tightly around the cable. The 80 coils are by this case held crosswise, while for the support lengthwise four rods, *i*, are hooked at one end over the flange *c* of one head, and provided at the opposite end with nuts *j*, which are screwed up tight on the other head, thus 85 holding the said heads, the cylindrical case, and the contents thereof solidly together. The reel may now be changed into a simple cable-drum (which is a cylindrical case containing 90 insulated wire or any other cable) by unscrewing the nuts which hold the segments *W* clamped tightly between the heads *U* and journals *V*, then drawing out the journals, whereupon the segments will collapse, so that they 95 can be drawn out through the center hole, *k*, (see Fig. 7,) leaving the cable coiled intact. Afterward a thimble or ring, *l*, is preferably 100 fitted into the central flange, *d*, of one of the heads *U*, whence its journal was removed to facilitate the paying out of the cable, and the 105 drum is ready for use.

I will now turn to Figs. 9, 10, and 11. In place of a movable center barrel, as before described, sleeves *X* are fitted into heads *U'*, and are furnished with shoulders projecting 110 through central openings, *k'*, in said heads, and around which simple plate-segments *W'* are kept in position by drawing the two sleeves and heads together by one central bolt, *Y*, passing through them, and fitted with nuts *m*, 115 screwed up on the outside. The ends of this bolt *Y* serve as the journals on which the reel rotates. The cylindrical case *Z'*, which incloses the cable after being coiled, is not hinged at the bottom, but is made light enough to, 120 spring open and around the cable, and is tightened by bolts *h'*, in the same manner as before described. The four rods *i'*, which secure the heads lengthwise, are hook-shaped at both ends, one of the heads *U'* having three 125 cornered notches, *n*, (three in number, or as many as there are rods *i'*,) cut into the outer

flange, so that the rods i' , after being hooked over the flange of the other head, can be dropped into these notches and tightened up by forcing them along the inclined faces of the notches.

5 Turning now to Figs. 12, 13, and 14, U^2 are heads consisting of plain disks without any flanges, but provided with a peripheral groove, o . The center barrel, W^2 , is solid (wood or metal) and slightly conical. It is 10 passed through central holes, k^2 , in the heads, and is keyed at both ends by keys o' , or at the smaller end alone if the larger end is fitted with a shoulder. The heads U^2 are kept at a given distance by wrapping around the barrel 15 a sheet of hard rubber, k^3 , or any other substance of sufficient stiffness susceptible of closing together transversely when the barrel is removed. After the cable is wound on the same it is inclosed by a light sheet of metal; 20 (such as brass,) Z^2 , the two lateral edges being crimped or rabbeted, (as are the edges of sheet-tin in making tin pails, &c.,) so as to fit into the grooves o around the edges of the heads U^2 , where they are kept in position by copper 25 wire, marlin-lines, or their equivalents, passed around the metal sheet in the said grooves and securely twisted or tied together, thus answering the double purpose of the lateral bolts h and h' and the longitudinal bolts i and i' , before described. The longitudinal edges of Z^2 are shown as fitted with handles p , to facilitate the lifting of the drum. The ring l , through which the cable pays out, as before 30 described, is here dispensed with, and instead of it a tube, q , is fitted in such a manner that its bell-mouth reaches into the center of the drum, where its rounded edges lead the cable in such a manner as not to come in contact with the square edges of holes k^2 .

35 40 What I claim as my invention, and desire to secure by Letters Patent, is—

1. The combination, in a floating marine torpedo, of electric-circuit wires and a pin or bar arranged in a slideway in the bow of the 45 torpedo, and adapted to complete said circuit and effect the firing of the torpedo on contact with any object, substantially as specified.

2. The combination, with a marine torpedo, of an electric circuit, projections H I in electric communication with said circuit, the firing pin or bar A A' , and the resistance-coil J , substantially as specified.

3. The combination, with a marine torpedo and an electric circuit therein, of two resistance-coils in electric communication with the electric circuit, and a pin, bar, or equivalent device for cutting out one of the resistance-coils, so as to effect the firing of the torpedo, substantially as specified.

4. The combination, with a marine torpedo, 60 an electric circuit therein, and an electric paying-out cable, of two resistance-coils, a pin, bar, or equivalent device for cutting out one of the resistance-coils on the contact of the device with any object, to thereby effect the automatic firing of the torpedo, and a device in communication with the paying-out cable for cutting out the other resistance-coil, to thereby effect the firing of the torpedo at the will of the operator, substantially as specified. 65

5. The combination, in a marine torpedo, of the exhaust-pipe of the engine and a hollow propeller-shaft, whereby the motive agent may be exhausted from the engine through the said shaft without passing into the propeller and 75 beyond or aft the propeller.

6. The combination, in a marine torpedo, of a hollow propeller-shaft and an immovable exhaust-pipe of the engine passing through such propeller-shaft, for the purpose of exhausting the motive agent through such propeller-shaft, substantially as specified. 80

7. The combination of a hollow propeller-shaft, an exhaust-pipe from an engine extending through such shaft, and a valve for automatically closing the exit of said exhaust-pipe when the engine is not exhausting, substantially as specified. 85

8. The combination, with one of the heads of a reel provided with an opening, of a thimble fitted to said opening, substantially as specified. 90

9. A cable-reel consisting of two heads, rods for holding said heads together at their periphery, a shell inclosing the space between the heads and made independently of said rods, and a detachable core which is removed to permit of the paying out of the cable from the inside of the coil, substantially as specified. 95

10. A cable-reel having heads and side rods 100 and a round-edge delivery-orifice for the cable, as described.

11. A reel composed of heads U , a collapsible body, W , journals V , and rods e , substantially as specified. 105

12. The combination, with a marine torpedo, of a cable-reel having one of its heads provided with an opening for the exit of the cable, said reel being arranged lengthwise of the shell or hull of the torpedo and in a compartment thereof, substantially as specified. 110
